[**] Term: 14 Years

Primary Examiner—A. Hugo Word

Assistant Examiner—Celia A. Murphy

Attorney, Agent, or Firm—Richard C. Litman

[21] Appl. No.: 345,526

CLAIM

[22] Filed: May 1, 1989

The ornamental design for a combined applicator and
remover for contact lens, as shown and described.

[52] U.S. Cl. D16/124; D9/373

DESCRIPTION

[58] Field of Search D3/30.1, 34; D9/301,
D9/338, 373, 374, 375, 376; D16/124;
D24/117, 118, 141, 150; D28/7; 215/1 C, 31;
294/1.2; 606/107

FIG. 1 is a top plan view of a combined applicator and
remover for a contact lens showing my new design;
FIG. 2 is a left side elevational view thereof;
FIG. 3 is a right side elevational view thereof;
FIG. 4 is a front elevational view thereof, the rear being
a mirror image;

FIG. 5 is a bottom plan view thereof;

FIG. 6 is a perspective view thereof; and

FIG. 7 is a sectional view taken on line 7—7 of FIG. 1
showing the design in the position of use, and the bro-
ken lines showing a contact lens and case being for
illustrative purposes only and claiming no part of the
claimed design.
